UNITED STATES PATENT OFFICE

CARL H. LARSSON, OF CHICAGO, ILLINOIS

SOUND AMPLIFIER

Application filed February 24, 1928. Serial No. 256,535.

This invention relates to sound amplifying apparatus which may be adapted for various purposes but which is particularly intended for use in connection with phonographs or 5 radio receiving apparatus.

The desirability of having some form of amplifier which will provide true sound or tone amplification has been long recognized but has been found exceedingly difficult to 10 accomplish. The present invention is intended to provide sound or tone amplification which will be true and correct to the fullest degree possible whereby all of the sound vibrations within the audible range 15 will be amplified and projected with as little distortion as possible so as to give most satisfactory and pleasing results.

Among the further objects of this invention are to provide a sound amplifier which 20 is particularly adapted for use in connection with phonographs or as a radio loud speaker; to provide a sound amplifier of a combined horn and reflector type; to provide a device of the character set forth having one or more 25 projecting surfaces and means to carry the sound from the place of production and directing it onto such surface or surfaces which in turn project it toward the hearer; to provide a device of the character set forth having 30 a receiving throat which connects with a bifurcated horn or sound passageways having their outlets directed toward a reflecting surface or surfaces; and to provide such other advantages and novel features as will 35 be described more fully hereinafter.

In the accompanying drawings illustrating this invention;

Figure 1 is a front view of my improved 40 device or amplifier shown in cabinet form;

Figure 2 is a cross sectional view taken 45 on the line 2—2 of Figure 3; and

Figure 3 is a vertical sectional view taken 50 on the line 3—3 of Figure 2; and

Figure 4 is a vertical sectional view taken 55 on the line 4—4 of Figure 3.

In the particular form of the device as 60 shown in these drawings, the parts are mounted in a cabinet or box 6 which may be made in any desired form and which may 65 serve to enclose the phonograph reproducer

mechanism or parts of a radio receiving apparatus if desired. The amplifier has an inlet throat or column 7 which passes through a hole in the top 8 of the cabinet and which is adapted to receive or be connected with 55 the tone arm of a phonograph or a radio reproducer element. The throat 7 leads to a bifurcated passageway comprising horns or branches 8 and 9 which extend outwardly toward the sides 10 of the cabinet and downwardly, as shown particularly in Figure 3. When the throat is positioned adjacent to the back 11 of the cabinet as shown in Figure 4, these branches or horns also bend or turn 60 forwardly toward their lower ends to a considerable degree. While the throat 7 is preferably round, the branches or horns 8 and 9 are preferably rectangular in cross section and gradually increase in size toward their lower ends where they are connected respectively with downwardly extending projections or extensions 12 and 13 which are curved or arranged so as to bring their mouths toward the back of the cabinet and which have substantially lateral or side outlet openings 65 14 and 15. The sound passageways or horns lead into a somewhat peculiarly shaped outlet or outlet chamber which opens toward the front of the cabinet and extends through the front wall 16 thereof, as shown particularly in Figure 3; the sides 17 and 18 of this outlet chamber are preferably arranged so that they converge toward the back of the cabinet.

The bottom of the chamber is formed by 85 the bottom 19 of the cabinet. The top comprises an arch or dome 20 which is also arranged at an angle, as shown in Figure 4, so that there is a general enlargement of the chamber from the back toward the front. 90 The back 21 of the outlet chamber which preferably comprises a sounding board is provided with two forwardly facing vertically extending deflecting surfaces or faces 22 and 23 which unite in a central vertical rib 95 24. These surfaces are in the main approximately in the form of quarters of cylinders but unite or coalesce with somewhat similarly shaped deflecting surfaces in the corner blocks or side resonators 25 and 26 100

at the mouths of the horns to form substantially semi-circular deflecting surfaces, as shown particularly in Figure 2.

The upper portion of the back is also curved forwardly, as shown at 27, where it unites with the dome or arch 20 and is curved forwardly, as shown at 28, where it unites with the bottom 19. This arrangement of the back and outlet chamber as a whole is such as to project the sound or tone forwardly in the most natural manner. The outlet chamber is preferably provided with doors 29 at the front which may serve to protect the inner parts and may also serve as valves for controlling the tones from the amplifier. A screen or grill 30 is also preferably arranged at the front of the outlet chamber which may serve not only for ornamental purposes and concealing or protecting the inner parts but also for the purpose of softening the tones if desired.

While any suitable material or materials may be utilized for making my improved sound amplifier or loud speaker device, I have found that particularly good results may be obtained by making the entire device of wood. The horns or conducting passageways from the throat to the outlet or resonant chamber are preferably made of sufficiently thin wood so that the walls thereof will be resonant while the back 21 of the outlet or resonant chamber may be formed of a thicker board or boards, for instance in the ones constructed this back or sounding board is approximately one-half inch in thickness.

When a sound or tone is directed into the throat or opening 7, it passes downwardly and is divided on the relatively sharp edge or projection between the horns, a portion of the sound passing downwardly through each horn where it is amplified and eventually passes out through the openings 14 and 15 into the central outlet or resonant chamber. As the sound passes out through these openings, it is deflected or thrown forwardly into two areas which meet along the vertical ridge or rib 24 and pass out through the open front of the amplifier. The rib 24 or forward portion of the central resonator also serves in the nature of a sound post for the dome or top sound board 20. It will also be noted that the shape of the back, as well as the top, bottom and sides of the outlet or resonant chamber is such that the sound or tones will tend to be thrown forwardly from all positions.

I have found from actual use that this construction is such that reproductions made by phonographs as well as the output of radio receiving elements will be amplified so that the entire range of audible vibrations, as produced by various musical instruments as well as by the voice will have their natural and proper tones without distortion.

It will be noted that various changes may

be made in the details of construction and arrangement of the parts, as well as in the variety of the materials used for constructing the amplifier without departing from the aim and purpose of this invention; therefore I do not wish to be limited to the exact details herein shown and described, except as specified in the following claims, in which I claim:

1. A sound amplifier comprising an inlet throat, two tortuous passageways leading downwardly from said throat, an outlet chamber positioned between said passageways and spaced therefrom and having a back with vertically arranged concave deflecting surfaces at either side thereof, said passageways having openings into said chamber which are directed toward said deflecting surfaces.

2. In a device of the character set forth, the combination of a resonant chamber having diverging lateral walls and having a back with a central vertical forwardly extending projection with curved sides, a pair of horns having outlet openings in the sides of the chamber, said horns being mounted at the sides of the chamber and spaced therefrom and being united in a common inlet pipe.

3. In a device of the character set forth, the combination of a cabinet, an amplifying chamber in said cabinet having an opening through the front wall of the cabinet and having a sound deflecting rear surface, an inlet throat arranged above said chamber, and passageways leading from the throat downwardly and over the sides of the recess and having outlet openings into the sides of the chamber.

4. The combination with a cabinet, of an outlet or resonant chamber open to the front of the cabinet, doors for closing said opening, said chamber having a rear wall with a central vertical projection provided with concave sides, a sound receiving inlet at the top of the cabinet, passageways leading from said inlet over the sides of the chamber and downwardly and spaced from the chamber and cabinet, said passageways increasing in area from the inlets to their outlets which outlets open into the sides of the chamber, said passageways having curved walls adjacent to the outlets for directing the sound laterally into the chamber and against the sides of said projection.

5. A device of the character set forth, comprising an outlet chamber having an open front with diverging side walls, and an arched top wall, the back of the chamber having vertically-arranged curved surfaces meeting on a median line and forming a projection at the center of the chamber, means for closing the open front of the chamber, passageways leading from the sides of the chamber forwardly, then up and rearwardly and inwardly and uniting in a common inlet, said

passageways being free from the chamber throughout their entire length, except at the points where they connect therewith, substantially as described.

6. In a sound amplifier, the combination of a sound board, a resonance chamber opening outwardly from the sound board, a plurality of sound passageways leading from a source of sound and directed toward the sound board, said passageways being located entirely without said chamber and spaced therefrom, and deflecting means coacting with the sound board and said passageways for directing the sound forwardly through the resonance chamber.

7. The combination with a cabinet, of a sound board mounted therein, duplex tapering horns leading from a common inlet and having their large ends directed toward the sound board, a chamber arranged between the horns which is spaced therefrom and facing outwardly, said horns having openings into the sides of said chamber, and deflectors which are curved in both vertical and horizontal planes coacting with the sound board and adapted to direct the sound from the two horns outwardly through the outlet passageway in substantially parallel lines.

8. A sound amplifier, comprising a cabinet having a sound board mounted in the back thereof, two sound horns leading from the top of the cabinet and having their ends directed toward the sound board and having openings in the sides thereof which lead into the resonance chamber, a resonance chamber arranged between the horns and opening toward the front of the cabinet, said chamber being separated from the horns, and curved resonators secured to the sound board and adapted to guide the sound from the horns and sound board forwardly through the resonance chamber.

9. An acoustical amplifier comprising a cabinet with an amplifying chamber with its side walls spaced from the side walls of the cabinet, means forming a divided sound inlet with amplifying horns extending therefrom at the sides of the cabinet between the outer side walls and the amplifying chamber and out of contact therewith, and means forming curved connecting passageways between each horn and the rear of the amplifying chamber.

10. An acoustical amplifier comprising a cabinet with a central amplifying chamber opening forwardly and having its side and top walls spaced from the walls of the cabinet, horns leading from the top of the cabinet to the sides of the amplifying chamber and out of contact with the walls of the cabinet and amplifying chamber, and means including a central resonator forming a continuous guide for sound waves from the horns to the amplifying chamber for merging the sound

waves in the same direction of amplification through said chamber.

11. A sound amplifier comprising a cabinet with a central amplifying chamber having its side walls spaced from the side walls of the cabinet to form spaces, two amplifying horns arranged in said spaces one on either side of the cabinet, said horns having their ends directed toward the back of the cabinet, and passageways from the horns into the amplifying chamber.

12. A device as per claim 6, having a sound board mounted at the back of the cabinet and having two curved side resonators, and a central resonator which is curved on either side in a horizontal plane and which is curved at the top and bottom in a vertical plane, said resonators forming the rear portions of the passageways from the horns to the amplifying chamber.

13. A sound amplifier having a resonance chamber provided with an arched top and having a central-resonator with concave sides and forwardly curved upper and lower ends in the back thereof, said top being secured to the upper end of the resonator, and said resonator being arched at its upper end to correspond with the arch of the top.

14. A sound amplifier comprising an outlet chamber having a sound board at the back thereof and open at the front and having a plurality of horns leading from a common inlet and opening into the sides of the chamber, said horns being spaced from the chamber and said chamber having no obstructions therein or in the outlet thereof.
